UNITED STATES PATENT OFFICE

GEORGE W. O'KEEFFE, OF DORCHESTER, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

THERMAL CUT-OUT

Application filed January 30, 1926. Serial No. 85,003.

This invention relates to protective devices, as thermal cut-outs, for electric circuits and is intended as an improvement on the invention disclosed in my co-pending application Serial No. 755,847, filed December 11, 1924.

The thermal cut-out set forth in my above application includes a casing containing two separable current-carrying members united by a material adapted readily to melt by the heat of the current traversing the cut-out, with means to separate the current-carrying members rapidly when the uniting material melts, whereby to interrupt the circuit.

The present invention has for an object the provision of means to entrap the gases and metal vapors and particles formed by the arc, during circuit interruption, and to prevent the metal vapors from condensing upon the wall of the enclosing casing and forming a conducting metal film between the circuit terminals.

A further object is to provide a single-use enclosing casing which surrounds the current-carrying members and which is adapted to enclose the circuit-interrupting arc and receive and retain the metal vapors and particles, which container is adapted to be thrown away after a circuit-interrupting arc has taken place within it.

A further object is to provide means disposed adjacent the fusible mass to cool and condense the condensable metal vapors formed upon circuit interruption.

A yet further object is generally to improve the construction of fusible cut-outs for electric circuits.

Fig. 1 is a side elevation of a thermal cut-out embodying my invention.

Fig. 2 is an enlarged sectional elevation taken through the vertical axis of Fig. 1.

Fig. 3 is a perspective view, partly in section, of the fusible link embodying the invention.

Fig. 4 is a plan view of the cut-out of Fig. 2 with the cover removed and with the fusible link in current-carrying position.

Fig. 5 is a view similar to Fig. 4 but illustrating the disposition of the component parts of the fusible link after the device has

operated to interrupt the circuit through it.

As here shown, the thermal cut-out embodying the present invention includes a casing 10 of insulating material formed with a recess 12 in the upper portion thereof, which recess is normally closed by a removable cover 14. The casing is provided with an integral boss 16 which supports a screw-threaded shell 17 which is adapted to be screwed into a suitable socket and make connection with one of the terminals of the circuit to be protected by the cut-out. Said boss is also provided with a contact member 18 at its lower end, which member is adapted to make contact within the socket with another terminal of the circuit to be protected. A post 20 is disposed within said recess 12 and within a recess 22 in said boss and is screw-threaded rotatably within said contact member 18 and is adapted to rotate in its connection therewith. A spring 24 encircles said post and has its ends connected respectively to said post and to said casing and is adapted to urge said post for rotation. Rotary movement of said post is normally restrained by the fusible link hereinafter to be described; and the rotation of said post is limited by the engagement of a laterally-extended link-holding arm 26 thereof with an abutment 28 of said casing. Said screw-threaded shell 17 is provided with a contact terminal 30 which extends upwardly into the recess 12 in a position remote from said abutment 28 and is provided with a binding screw 32 by which mechanical and electrical connection is made with one end of the fusible link. The link-holding arm 26 is provided with an upwardly-extended hook 34 over which the other end of the fusible link is adapted to be received.

The fusible link comprises two separable current-carrying members 36 and 38 herein shown as composed of wire and preferably wire having a relatively high electrical resistance and adapted to become heated by the passage of current through them. The proximate ends of said members are juxtaposed and united mechanically and electrically by a mass 40 of solder or some readily fusible metal which is adapted to fuse or melt

when the link becomes sufficiently heated and thereby to permit the current-carrying members to be separated and consequently to interrupt the circuit. Said members are provided with reflexed or hook-terminals 42 and 44, one of which hooks is adapted to be received under the binding screw 32 and the other of which is disposed over the hook 34 of the arm 26 carried by the post 20. The 10 spring 24 associated with said post is arranged to exert a tension upon the two parts of the fusible link and to separate them rapidly when the fusible metal melts and releases them, whereby rapidly to attenuate the circuit-interrupting arc and interrupt the circuit.

After the fusible link has been severed the parts thereof are adapted to be thrown away and replaced by a new and similar link.

20 The apparatus above described is essentially the same as is set forth in my above-named application.

In the operation of the cut-out as above described it has been found that, under certain conditions, the metal particles and vapors, formed upon the drawing of the arc, condense and collect upon the wall of the recess 12 and tend to form a metal conducting film thereon which lies between the terminals 20 of the cut-out. The presence of such a conducting film is undesirable as it reduces the open-circuit insulation value of the device and also presents the possibility of the circuit-interrupting arc passing to the film and thereby rendering the extinction of the arc difficult. In addition, upon heavy loads, so much metal may be vaporized as to build up a substantial and undesirable fluid pressure within the casing.

40 For these and other reasons it is an object of this invention to provide means to catch and absorb the gases and metal particles and condense and retain the metal vapors formed upon circuit interruption and to keep them 45 confined at the instant of circuit interruption and to prevent the metal vapor from being condensed and the metal particles from collecting on the inner wall of the casing. The aforesaid means comprises essentially a cylindrical cover or tube 46 which is disposed loosely upon the fusible link, to cover the fusible metal thereof. The tube preferably encloses the straight portion of the link on both sides of the fusible metal and is held in 50 place by the reflexed ends of the link, which ends may be reflexed after the tube is in place. Said tube is composed of some suitable heat-resisting and electrically insulating material, as asbestos. The tube preferably is somewhat porous. When the mass 40 of fusible metal melts under heat, the circuit-interrupting arc is drawn within the insulating tube. The tube acts to confine the arc gases and metal vapors and particles in close proximity 55 to the link-members. The arc products pass

into the pores of the tube and are prevented from circulating throughout the casing, although the ends of the tube are open and the arc gases may escape to some extent from the open ends. The metal vapors and melted particles of metal are collected and condensed upon the cool inner wall of the tube. After circuit-interruption the tube will be found upon either one or the other of the separable components of the fusible link, one of the components having been withdrawn through the open end of the tube, or on the bottom of the recess, free from the separated components. After a circuit-interruption the tube with any internal deposit of metal particles it may have received is adapted to be thrown away, together with the separated link-components, and replaced by a new tube on a new link. Used in this manner, the cut-out is always provided with a fresh surface upon which the metal particles can collect and the metal vapor can condense so that the inner wall of the link-compartment is maintained free from any material metal deposit. The formation of a substantial gas pressure is retarded, also.

The tube above set forth has been found materially to increase the circuit-interrupting ability of the cut-out.

I claim:

1. A fusible link for an electric cut-out comprising two separable current-carrying members united by a mass of readily fusible material, and a porous tubular cover of electrically insulating and heat-resisting material enclosing said fusible mass and adjacent portions of said current-carrying members loosely and adapted to retain in the pores the metal particles of the fused material, said current-carrying members extended outwardly beyond the open ends of said cover and terminated in reflexed ends provided with hooks, the ends of said cover being terminated at and held from displacement on said link by said reflexed ends.

2. An electric cut-out comprising an enclosing casing provided with an outer screw-threaded terminal shell, a shaft rotatably-supported within said casing along the axis of the shell, said shaft having a laterally-extended arm terminated close to the wall of said casing, means urging said shaft to revolve said arm transversely of said casing-axis, a fixed circuit terminal disposed within said casing, a link disposed within and adjacent the wall of said casing and connecting said fixed terminal and the end of said arm and adapted normally to hold said arm from movement, said link comprising two separable current carrying members having proximate ends united with a readily fusible material and having hooked outer ends engaging said fixed terminal and arm, and a porous tubular cover of electrical insulating and heat resisting material enclosing loosely said fus-

ible material and the proximate ends of said current carrying members, said link characterized by the fusing of the fusible material connecting its current carrying members up-
5 on overload and releasing said current carrying members for separating movement under the action of said arm and shaft, and said porous insulating tubular cover characterized by retaining within its pores the metal par-
10 ticles of said fusible material and holding the particles against contact with the side walls of said enclosing casing.

3. A thermal cut-out for electric circuits of the screw plug type including a tubular insulating casing having external screw threads at one end by which it is adapted to be supported and an enlarged internal recess at its other end, a rigid conducting member extended axially of said tube and spaced from 15 the insulating side walls thereof, relatively separable terminal members disposed within said recess, a fusible link disposed in said recess at one side of said axial conducting member and closely adjacent the side walls there-
20 of and connected with and normally restraining said terminal members from movement, said link comprising two separable contact-carrying members united with a readily fusible material and a porous cover of electric-
25 ally insulating and heat-resisting material loosely enclosing said fusible member and adjacent portions of said current-carrying members and characterized by holding in its pores metal particles of said fusible material and preventing the formation of a conducting film on the proximate side wall of said casing.
